DESIGN.

A. SNOW, Jr.
GLASS RECEPTACLE.

No. 28,179.

Patented Jan. 18, 1898.

UNITED STATES PATENT OFFICE.

ANDREW SNOW, JR., OF NEW BEDFORD, MASSACHUSETTS.

DESIGN FOR A GLASS RECEPTACLE.

SPECIFICATION forming part of Design No. 28,179, dated January 18, 1898.

Application filed November 3, 1897. Serial No. 657,298. Term of patent 7 years.

To all whom it may concern:

Be it known that I, ANDREW SNOW, Jr., of New Bedford, in the county of Bristol and State of Massachusetts, have invented a new 5 and useful Design for Glass Receptacles, of which the following is a specification.

Referring to the accompanying drawings, Figure 1 is a side elevation of a glass receptacle embodying my design. Fig. 2 is another side elevation taken at a different angle of the same receptacle, and Fig. 3 is a cross-sectional view on the line 3 3 of Figs. 1 and 2.

As represented in the drawings, the leading 15 or material feature of my invention consists of rows of smooth-surfaced concavities extending from the bottom of the receptacle toward the top thereof and rows of parallel prism-like ribs, the rows of concavities and 20 ribs alternating.

A indicates the rows of smooth-surfaced concavities *a*, and B the rows of prism-like ribs *b*. The rows of concavities and ribs are vertically arranged. As the receptacle tapers upwardly from the bottom the concavities *a* 25 gradually diminish in area from the bottom of the receptacle upwardly.

What I claim is—

The design for a glass receptacle as herein shown and described. 30

In testimony whereof I have signed my name to this specification, in the presence of two subscribing witnesses, on this 27th day of September, A. D. 1897.

ANDREW SNOW, JR.

Witnesses:

FRANCIS K. ALLEN,
WILLIAM A. CLARKE.
